[57] CLAIM

The ornamental design for computer chassis a rack for
attachment to a mobile computer cart, as shown and
described.

DESCRIPTION

FIG. 1 is a top, front, and left side perspective view of
a computer chassis rack for attachment to a mobile
computer cart showing our new design, the broken-line
disclosure of a portion of the computer cart being for
illustrative purposes only and forming no part of the
claimed design;

FIG. 2 is an enlarged front elevational view thereof;
FIG. 3 is an enlarged top plan view thereof;
FIG. 4 is an enlarged rear elevational view thereof;
FIG. 5 is an enlarged bottom plan view thereof; and,
FIG. 6 is an enlarged left side elevational view thereof,
the right side being a mirror image of that shown.

FIG. 1

FIG. 6

FIG. 2**FIG. 3**

FIG. 4**FIG. 5**
